HIS ATTORNEY

UNITED STATES PATENT OFFICE.

GEORGE A. SEIB, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 919,254.

Specification of Letters Patent. Patented April 20, 1909.

Application filed January 8, 1907. Serial No. 361,301.

To all whom it may concern:

Be it known that I, GEORGE A. SEIB, citizen of the United States, and resident of Syracuse, in the county of Onondaga and State of New York, have invented certain new and useful Improvements in Type-Writing Machines, of which the following is a specification.

My invention relates to typewriting machines and more particularly to billing devices.

One of the objects of the invention is to provide a simple and efficient billing device particularly adapted for "condensed record" work and by the use of which the mind of the operator is relieved from making mental calculations in properly positioning the sheets and which enables the operator to properly position the sheets in the machine with mechanical accuracy.

A further object of my invention is to provide devices of the character specified which are in the nature of attachments which may be readily applied to existing forms of typewriting machines without changing the structural features of said machines.

To the above and other ends which will hereinafter appear, my invention consists of the features of construction, arrangements of parts and combinations of devices to be described in the following specification and particularly pointed out in the appended claims.

I have shown the devices of my invention applied to a Monarch machine to which they may be readily attached without changing the structural features of said machine, though it should be understood that the devices may be employed in other styles of typewriting machines.

In the accompanying drawings, Figure 1 is an enlarged front elevation partly in section showing the upper portion of a type-writing machine with the devices of my invention applied thereto; parts not essential to an understanding of the present invention being omitted. Fig. 2 is a fragmentary right-hand end elevation of the same with the right-hand finger wheel sectioned away. Fig. 3 is an enlarged detail perspective view of the stop carrying disk, the supporting screws therefor being shown in section. Fig. 4 is an enlarged detail perspective view of the indicator carrying disk. Fig. 5 is an enlarged detail fragmentary plan view showing

the right-hand end of the platen frame or carriage and the fixed stop carried thereby.

The top plate 1 of the machine is provided with upwardly extending standards 2 to which fixed rails 3 are secured by screws 4, 50 the rails or tracks 3 being grooved on opposite faces as at 5. Anti-friction balls 6 are received in the grooves in the rails 3 and are likewise received in oppositely disposed grooves 7 in a rear carriage bar 8. Forwardly projecting arms 9 and 10 project from the ends of the bar 8 and are provided with bearing openings in which the platen shaft 11 is mounted. The outer ends of the shaft 11 carry finger wheels 12 and a platen 13 is secured to the shaft by a screw 14 which is received in a threaded opening in a hub 15 of the right-hand platen head 16 secured in the usual manner by wood screws to the core 17 of the platen. A left-hand platen 18 is formed with ratchet teeth 19, which constitute a line spacing wheel with which a line spacing pawl 20 cooperates. The line spacing pawl is actuated in the usual manner by a finger piece 21. A detent 80 roller 22 carried by a spring 23 secured by a screw 24 to the platen frame or carriage, bears against the teeth 19 of the line spacing wheel.

The parts thus far described are or may be of the usual construction employed in the Monarch machine.

The right-hand platen head 16 is provided with three screws 25 situated a uniform distance from the platen shaft as shown in Figs. 2 and 3 and forming bearings for a stop carrier or disk 26 and for a dish friction spring 27. As shown in Fig. 3, the disk 26 has a circular central opening through which the screws 25 project, so that said disk is free to rotate with relation to the platen. As shown in Fig. 1, the heads of the screws 25 constitute means for limiting the movement of the stop carrying disk to the right, and the dish friction spring 27 bearing at its outer face against the stop carrier or disk 26 and bearing at its opposite face, near the periphery thereof, against the right-hand platen head, presses said disk against the heads of the screws 25 and constitutes a frictional connection between the stop carrier and the platen. The stop carrier 26 is provided with a laterally projecting stop pin 28 which is riveted to the disk as indicated at 29 in Fig. 1. The construction and arrangement of the

parts are such that the disk 26, which is provided with a knurled periphery or edge 30, is adapted to receive a rotative adjustment on the bearing screws 25 around the axis of the platen and to turn with the platen by reason of the dish spring 27 interposed between the disk 26 and the right-hand platen head except when arrested as will hereinafter more clearly appear when the platen may turn independently of the disk. Situated at the outer side of the disk 26 is a second disk or carrier 31 provided with an indicator which, in the present instance, is in the nature of a laterally projecting pin 32 riveted to the disk as indicated at 33 at Fig. 1. The indicating pin 32 is situated at the same distance from the axis of the platen as the stop pin 28 although it is out of the path of said stop pin. A bearing sleeve 34 for the platen shaft is received in an opening in the end plate 10 of the platen frame or carriage and is secured against movement in said opening by a set screw 35 which extends through a threaded opening in the end plate 10 and bears at its inner end against the sleeve 34. This bearing sleeve is provided at its inner end with an enlarged cylindrical member 36 which, in the Monarch machine, constitutes a ball bearing thrust box for the platen. The periphery of this box in the present instance constitutes a bearing for a hub-like portion 37 which projects from the disk 31 so that the disk 31 is adapted to turn around the axis of the platen on the member 36. From an inspection of Fig. 4 it will be seen that a curved leaf spring 38 is riveted at one end as at 39 to the hub 37, whereas the opposite or free end of the spring carries a friction device or pin 40 riveted thereto at 41. This friction pin 40 passes through an opening 42 in the hub 37 and the inner conoidal end 43 of the pin is received in a circumferential or peripheral groove 44 in the periphery of the member 36, said groove being V-shaped in cross section. By this arrangement the disk 31 is prevented from accidental displacement longitudinally of the platen from the bearing member 36 on which the hub 37 is mounted. At the same time the pressure of the spring 38 on the pin 40 produces a frictional contact between the pin and the member 36 so as to retain the disk 31 in any position to which it may be rotatively adjusted around the axis of the platen.

A fixed stop 45 is secured to the right-hand end plate or bar 10 of the platen frame or carriage by a screw 46. This fixed stop is in the nature of an angle iron or bracket, one end or foot portion 47 of which is secured by the screw 46 to the carriage. A portion 48 of the stop extends longitudinally of the platen and is bent upwardly and forwardly at 49 to provide a stop member or portion which cooperates with the rotary stop 28. From an inspection of Figs. 1 and 2 it will be seen that the portion 48 of the fixed stop

extends outside of the peripheries of the two disks 26 and 31 but at the upwardly and forwardly extending end or arresting portion 49 of the stop extends into the path of the rotary stop 28; and that said fixed stop 45 does not extend into the path of the pin 32 and does not coat with said pin or the disk 31 which carries it.

From the foregoing description it will be understood that the disk 31 which is knurled on its periphery or edge as indicated at 50 may be turned around the axis of the platen to bring the indicator or laterally projecting pin 32 to any desired position and that the disk will be retained in its adjusted position by the frictional connection between said disk and the platen frame or carriage. It will also be seen that the stop carrying disk 26 will be rotated with the platen through the frictional connection between the platen and said disk until the stop 28 is brought into contact with the fixed stop 45 when the stop and disk 26 will be arrested and a further rotation of the platen may be effected after the stop has been arrested. It will likewise be seen that during the rotation of the stop 28 in one direction it is brought into registration with the indicating pin 32, that is to say, there is a time during the rotation of the stop pin 28 with the platen when said pin will be brought into alignment with the indicating pin 32.

For "condensed record" work it is necessary in the first instance to set the devices for the particular character of bill or invoice sheets to be employed. In order to do this the platen is first rotated forwardly or in the direction of the arrow in Fig. 2 until the rotary stop 28 which rotates therewith is in contact with the fixed stop 45 as shown in said figure. A bill or invoice sheet of the character to be employed is then introduced into the machine and a further forward rotation of the platen is effected until the point on the bill sheet where the first line of writing is to appear is brought to the printing line indicated by the dotted line a. It may be assumed, by way of example, that the forward rotation of the platen just described corresponds to twenty-six teeth of the line spacing wheel. During this forward movement of the platen the rotary stop 28 remains in engagement with the fixed stop 45 and the platen turns independently of the rotary stop. A rearward rotation of the platen or a rotation thereof in the direction opposite to that indicated by the arrow in Fig. 2 is now effected until the leading edge of the bill sheet is at the point where it was introduced into the machine or in other words is in the bight between the main feed rollers 51 and the platen.

The extent of backward rotation to be given the platen may be accurately determined by clicking the platen forward a tooth

of the line spacing wheel at a time until the proper point on the bill has been brought to the printing line, the operator counting the number of clicks or teeth. It has been as-
 5 sumed that this movement corresponds to the distance of twenty-six teeth of the line spacing wheel in the present example. It follows therefore that if it required a forward rotation of the platen for a distance of
 10 twenty-six teeth of the line spacing wheel to carry the bill sheet forward from the point where it was introduced into the machine to a position where it will be properly positioned to receive the first line of writing,
 15 then it will require a like extent of backward rotation to bring the leading edge of the bill sheet back to the point of introduction. During the backward rotation of the platen the rotary stop 28 will travel with it away
 20 from the fixed stop 45. It may be assumed that this twenty-six toothed space backward rotation of the platen will carry the stop 28 from the position shown in Fig. 2 around to a position corresponding substantially to the
 25 position of the stop 32 in said figure. The disk 31 is then adjusted around the axis of the platen until the indicating pin 32 is in alinement or register with the stop pin 28. The bill sheet is then removed and a forward
 30 rotation is imparted to the platen to carry the stop pin 28 away from or out of register with the pin 32 and into contact with the fixed stop 45. The devices are now set and a further setting of the parts is unnecessary
 35 until the style of bill heads is changed, that is to say until bill sheets with a larger or smaller printed heading are employed. After the devices have been set in the manner de-
 40 scribed, and the rotary stop 28 is in contact with the fixed stop 45, a record sheet, bill sheet and interposed carbon sheet are intro-
 45 duced into the machine with the leading edges of the sheets together or the bill sheet may be given a "lead" over the record and carbon sheets in the usual manner in order to bring the first line reproduced on the record sheet near the top thereof. The platen is then rotated forwardly until that portion of the bill sheet where the first line of
 50 writing is to appear, usually the date line, is brought to the printing line *a*. The operator then proceeds to write the bill and a carbon copy thereof will be reproduced on the con-
 55 densed record sheet. The operator then lines spaces, say a distance equivalent to three teeth of the line spacing wheel, in order to provide a proper space between the last line of the copy of the bill just reproduced on the record sheet and the first line of the copy of
 60 the next bill to be reproduced thereon. The written bill or invoice sheet may now be removed from the machine without disturbing the platen or the carbon and record sheets, or the bill sheet may be allowed to remain in
 65 the machine and be fed backwardly and for-

wardly with the record and carbon sheets during the subsequent operations until the bill sheet is fed forwardly to a point where it is no longer under the control of the paper feeding devices and may be readily removed from the machine. During the forward movement of the platen described above the stop 28 remains in contact with the fixed stop but after the bill has been completed and the platen given an additional three line space movement the platen will be turned rearwardly at which time the stop 28 will rotate with the platen away from the fixed stop 45. This backward rotation of the platen is continued until the stop 28 is brought into alinement or register with the indicating pin 32. This rearward rotation of the platen is sufficient to effect a rearward movement of the carbon and record sheets a requisite distance to receive a new bill sheet in its proper relation to the record sheet. The platen is then given a forward rotation until the stop 28 contacts with the fixed stop 45 or until the date line on the newly introduced bill is at the printing line. The operator then proceeds to write the second or newly introduced bill and a copy thereof will be reproduced through the interposed carbon sheet, the first line of the copy of the last bill on the record sheet appearing three line space distances from the last line of the copy of the preceding bill. This operation continues until the condensed record sheet is filled when a new one may be introduced and the work proceeded with as before.

It will be understood that after the devices are once set a backward and forward rotation and a three line space movement of the platen is all that is required to receive a new bill in proper relation with the record sheet and to properly position the bill sheet to receive the first line of writing and to provide for proper spacing between copies of the bills on the record sheet. The extent of forward rotation of the platen is determined by observing when the date line on the bill sheet reaches the printing line or when the stop 28 reaches contact with the fixed stop 45 and the extent of backward rotation of the platen is determined by the registration of the stop 28 with the adjustable indicating pin 32.

I have described one method of using my invention in connection with condensed record work but would have it understood that I do not limit myself to the method described and that my invention may be employed for other uses than condensed record work.

When I refer herein to the adjustable pin 32 as a fixed indicator it will of course be understood that this is intended to mean that the pin 32 remains fixed against rotary movement with the platen during billing operations.

Various changes may be made without departing from the spirit and scope of my invention.

What I claim as new and desire to secure by Letters Patent, is:—

1. In a typewriting machine, the combination of a rotary platen, a carrier connected to rotate with said platen, a stop carried by the rotary carrier, a coöperative fixed stop, 10 an indicator held against rotation with the platen and out of the path of the rotary stop but with which said rotary stop is adapted to register, and means for effecting a relative adjustment between said fixed stop and indicator.
2. In a typewriting machine, the combination of a rotary platen, a carrier connected to rotate with said platen, a stop carried by said rotary carrier, a coöperative fixed stop, 15 an indicator held against rotation with the platen and out of the path of the rotary stop but with which said rotary stop is adapted to register, and means for effecting a relative adjustment between said fixed stop and indicator.
3. In a typewriting machine, the combination of a rotary platen, a carrier frictionally connected to rotate with said platen, a stop carried by the rotary carrier, a coöperative fixed stop, 20 an indicator held against rotation with the platen and out of the path of but with which said rotary stop is adapted to register, and frictional means for affording a relative adjustment of said indicator.
4. In a typewriting machine, the combination of a rotary platen, a carrier frictionally connected to rotate with the platen around the axis of the platen and to allow a rotary movement of the platen independently thereof, a stop carried by said rotary carrier, 25 a coöperative fixed stop, an indicator with which said rotary stop is adapted to register, a carrier for said indicator, means for allowing an adjustment of said indicator and its carrier around the axis of the platen, and 30 means for holding said indicator against rotation with the platen and in the position to which said indicator may be adjusted.
5. In a typewriting machine, the combination of a rotary platen, a carrier frictionally connected to rotate with the platen around the axis of the platen and to allow a rotary movement of the platen independently thereof, a stop carried by said carrier, a coöperative fixed stop, 35 an indicator with which said rotary stop is adapted to register but which is out of the path of said rotary stop, a carrier for said indicator, said indicator and its carrier being adjustable around the axis of the platen, and frictional means for holding said indicator against rotation with the platen and in the position to which said indicator may be adjusted.
6. In a typewriting machine, the combination of a rotary platen, a disk adapted to 40 turn around the axis of the platen, operative connections between said disk and the platen whereby a rotation of the disk with the platen and a rotation of the platen independently of the disk is afforded, a stop carried by said disk, a coöperative fixed stop, 45 and an indicator with which the rotary stop is adapted to register but which is out of the path of said rotary stop.
7. In a typewriting machine, the combination of a rotary platen, a disk adapted to 50 turn around the axis of the platen, operative connections between said disk and the platen whereby a rotation of the disk with the platen and a rotation of the platen independently of the disk is afforded, a stop carried by said disk, a coöperative fixed stop, 55 a relatively fixed indicator with which the rotary stop is adapted to register but which is out of the path of said rotary stop, and means for effecting a relative adjustment between said fixed stop and indicator.
8. In a typewriting machine, the combination of a rotary platen, a disk adapted to 60 turn around the axis of the platen, operative connections between said disk and the platen, whereby a rotation of the disk with the platen and a rotation of the platen independently of the disk is afforded, a stop carried by said disk, a coöperative fixed stop, 65 a second disk adapted to turn around the platen axis and arranged beside said first mentioned disk, an indicator on said second disk and which is out of the path of said rotary stop but with which said rotary stop is adapted to register, and means for retaining 70 said second disk in any rotative position to which it may be adjusted.
9. In a typewriting machine, the combination of a rotary platen, a platen frame, a disk adapted to turn around the axis of the platen, frictional connections between said disk and the platen, whereby a rotation of the disk with the platen and a rotation of the platen independently of the disk is afforded, 75 a stop carried by said disk, a coöperative fixed stop carried by said platen frame, a second disk adapted to turn around the platen axis and arranged beside said first mentioned disk, an indicator on said second disk, and which is out of the path of said rotary stop but with which said rotary stop is adapted to register, and frictional means 80 between said second disk and the platen frame for retaining said second disk in any rotative position to which it may be adjusted.
10. In a typewriting machine, the combination of a rotary platen, a disk adapted to 85 turn around the axis of the platen, operative connections between said disk and the platen whereby a rotation of the disk with the platen and a rotation of the platen independently of the disk is afforded, a stop pin projecting laterally from said disk, a coöperative fixed stop, a second disk arranged beside said first mentioned disk and rotatively adjust- 90

able around the axis of the platen but normally held against rotation, an indicator pin projecting laterally from said second disk and out of the path of said stop pin but with which said stop pin is adapted to register, and means for retaining said second disk in its adjusted position.

11. In a typewriting machine, the combination of a rotary platen, a platen frame, a disk adapted to turn around the axis of the platen, frictional connections between said disk and the platen, whereby a rotation of the disk with the platen and a rotation of the platen independently of the disk is afforded, a stop pin secured to and projecting laterally from said disk, a coöperative fixed stop carried by the platen frame, a second disk arranged beside said first mentioned disk and rotatively adjustable around the axis of the platen but normally held against rotation, an indicator pin fixed to and projecting laterally from said second disk and out of the path of said stop pin but with which said stop pin is adapted to register, and frictional means between the platen frame and said second disk for retaining the latter in its adjusted position.

12. In a typewriting machine, the combination of a rotary platen, a carrier, a frictional connection between the platen and carrier for causing the carrier to rotate with said platen, a stop carried by the carrier, a coöperative fixed stop, and an indicator fixed against rotation with the platen and with which said rotary stop is adapted to register, the frictional connection between the platen and said rotary stop carrier comprising a dish spring bearing at one side against the platen and the other side against said stop carrier.

13. In a typewriting machine, the combi-

nation of a rotary platen, a carrier connected to rotate with said platen, a stop carried by the carrier, a coöperative fixed stop, an indicator fixed against rotation with the platen and with which said rotary stop is adapted to register, and means for adjusting a rotative adjustment of said indicator, said adjusting means comprising a flat spring connected with said indicator and a friction pin pressed by said spring into contact with a part that is fixed against rotation with the platen.

14. In a typewriting machine, the combination of a rotary platen, a carrier frictionally connected to rotate with the platen around the axis of the platen and to afford a rotary movement of the platen independently thereof, a stop carried by said carrier, the frictional connection between said carrier and platen comprising a dish spring bearing at one side against the platen and at the other side against said carrier, a coöperative fixed stop, an indicator with which said rotary stop is adapted to register but which is out of the path of said rotary stop, a carrier for said indicator, means for affording an adjustment of said indicator and its carrier around the axis of the platen, and frictional means for holding said indicator carrier against rotation with the platen and in the position to which said indicator and carrier may be adjusted, the frictional means for holding the indicator comprising a spring secured to the indicator and a friction pin against which the spring bears.

Signed at Syracuse, in the county of Onondaga, and State of New York this 5th day of Jany. A. D. 1907.
